The ornamental design for a mobile phone, as shown and described.

DESCRIPTION

FIG. 1 is a front perspective view of a mobile phone showing our new design;

FIG. 2 is a front elevation view thereof;

FIG. 3 is a rear elevation view thereof;

FIG. 4 is a left side elevation view thereof;

FIG. 5 is a right side elevation view thereof;

FIG. 6 is a top plan view thereof;

FIG. 7 is a bottom plan view thereof;

FIG. 8 is a rear perspective view thereof; and,

FIG. 9 is an enlarged detail view of the encircled portion shown in FIG. 8.

The evenly-spaced dashed broken lines in the figures depict portions of the mobile phone that form no part of the claimed design. The dot-dash broken lines in the drawings represent the bounds of the claim and form no part thereof. The dot-dot-dash broken lines in FIGS. 8 and 9 encircling the portion of the claimed design that is illustrated in enlargement in FIG. 9 form no part of the claimed design.
